UNITED STATES PATENT OFFICE.

WILLIAM R. CLYMER, OF CLEVELAND, OHIO, ASSIGNOR TO NATIONAL CARBON COMPANY, A CORPORATION OF NEW JERSEY.

BATTERY-LAMP.

1,212,907.

Specification of Letters Patent. Patented Jan. 16, 1917.

Application filed June 5, 1914. Serial No. 843,147.

To all whom it may concern:

Be it known that I, WILLIAM R. CLYMER, a citizen of the United States, residing at Cleveland, in the county of Cuyahoga and State of Ohio, have invented a certain new and useful Improvement in Battery-Lamps, of which the following is a full, clear, and exact description.

The invention relates in one aspect to the combination of a flashlight with lens adjusting means, and in another aspect to a resistance rheostat therefor.

It is well known that flashlight batteries, as well as the larger types of dry batteries, have a decreasing voltage during the life of the battery. The individual cells comprising the batteries have an initial E. M. F. between 1.5 and 1.6 volts and are used until this has decreased to $\frac{1}{2}$ or even $\frac{1}{3}$ volt. If three cells are used in series, the voltage applied to the lamp may therefore vary from 1.5 to 4.8 volts in certain cases. Furthermore, the decrease in voltage is more rapid when the cells are first placed into use than afterward. As a result of this, the greatest part of the service of such batteries is obtained at or below an E. M. F. of one volt. It is impossible to secure an incandescent lamp that will give good service over such a wide range of voltage. Instead of using a lamp suited for the initial or the final E. M. F., a lamp is employed that is adapted to a voltage somewhat below the initial value. For instance, a four volt or even a 3.6 volt lamp is used in connection with a battery giving an initial E. M. F. of 4.8 volts. The excess voltage sometimes causes the filaments to burn out and considerably shorten the life of the lamp. The unnecessary increased consumption of electrical energy at these voltages also decreases the life of the battery. In order to secure a maximum life for the battery as well as the lamp, I use a resistance rheostat to cut down the excess E. M. F. during the first period of the life of the battery. By the use of my device, either of two quantities of illumination may also be readily obtained by the user.

In the accompanying drawings, I have shown my invention embodied in the two most commonly used types of flashlights.

Figure 1 is a partial cross section of a pocket flashlight having a resistance and lens adjusting arrangement combined there-

with. Fig. 2 is an enlarged sectional view 55 of the switch and resistance attached to the casing. Fig. 3 is an enlarged view of the combined switch and resistance shown in Fig. 1 detached from the casing. Fig. 4 is a cross section of a tubular flashlight having a resistance and lens adjusting device combined therewith. Fig. 5 is an interior view of the cap of the flashlight shown in Fig. 4.

Referring to the drawings, more particularly Figs. 1, 2 and 3, the flashlight consists of a metal casing 1 having a removable bottom 2, for inserting or removing the battery 3 consisting of a plurality of dry cells. The battery is provided with two protruding terminals 4 and 5 connected respectively to the end carbon and zinc, though the reverse may be used. The spring terminal 4 maintains the battery in position and consists of a flat metal strip bent over so as to make electrical connection with the base of the incandescent lamp 6 which is threaded into an opening in the center of the metal reflector 7. In order to shorten the length of the lamp arrangement, the rim of the reflector 80 rests on the base of a tubular member 8 held in the casing 1. An open cap 9 is adjustably threaded over the ferrule 8 and a lens 10 is held in the cap by a coil spring 11. By changing the position of the cap 9 on the ferrule 8 the distance between the lamp and the lens is varied and the focus of the light rays is altered. In this way the spread of the light beams may be varied so as to be suitable for different purposes. 90

A further important feature of my improved flashlight resides in the novel contact arrangement fastened to the casing 1. This device consists of two flat and substantially parallel members 13 and 14 separated by an insulating block or sheet 15. The longer member 13 which is preferably of spring brass is riveted at one end to the casing and at the other end has an attached push button 16 which passes through an opening 17 100 in the casing. Spring 13 is connected to spring 14 through a resistance 19 and this preferably consists of an insulated resistance wire coiled tightly around the two springs as shown best in Fig. 3, to hold 105 them rigidly together.

By depressing the push button slightly so that the projection 18 is in contact with the

terminal 5 but not with the spring 13, the current will pass through the resistance by way of the members 13 and 14 to the casing 1, the tubular member 8, reflector 7, lamp 6 and spring 4 to complete the circuit. In this position the voltage and current acting on the lamp are decreased an amount depending on the ohmic resistance of the wire 19. With a terminal E. M. F. of 4.8, this would be sufficient to cut the lamp voltage down the required amount. When the button is further depressed, the end 18 bends, and the push button end of the spring 13 contacts with it, which short circuits the resistance 19 and subjects the lamp to the full battery voltage. When the battery is new, or if a diminished light is desired, the operator will push the button only enough to cause the end 18 to contact with the terminal 5. As the battery voltage decreases, or if a brighter light is desired, the button is pushed till the resistance is short circuited as described.

In the modification shown in Figs. 4 and 5, the same features as already described are adapted to a tubular battery having the cells 22 arranged end to end with the lamp in one end of the tube and the switch fastened to the cap which closes the other end. The lamp end of casing 21 has a reflector 23 therein with the lamp 24 threaded into a central opening. A lens 25 and a spring 26 are fitted in a cap 27 which is threaded on the casing. The cap and the casing are each threaded a sufficient distance to permit the focus of the lens to be adjusted for the purpose and in the manner already described.

The circuit closing and resistance devices are contained in the cap 28 which is threaded adjustably on the casing. A layer of insulation such as a disk 29 of fiber board or enameled sheet metal is inserted in the cap. As shown in Fig. 5, this disk has four inner lugs 30 punched up or raised from its surface and four outer lugs 31 similarly punched and spaced between the first mentioned lugs. To maintain the battery in good contact with the lamp a spring 32 is inserted between the disk and battery and is held in position by fitting one turn of the coiled spring under the lugs 30.

One end of a resistance coil 33 consisting of one or more turns is electrically connected to the bottom coil of the spring at 33' (Fig. 5) and the turns are fitted under the outer lugs 31 as shown in Fig. 5. The other end of the resistance is turned in toward the center of the coil and is fastened to a central rivet 36 passing through the cap. A second coil spring 34 somewhat shorter than the outer spring 32 is placed within it and is fastened to a rivet 36 by means of the eye 35. The rivet 36 passes through a coiled end or eye of the resistance 33 and through a large

opening 37 in the center of the cap, and clamps the contact spring 39 against the washer 38. The springs 32, 34, resistance coil 33, contact 39 and insulation disks 29, 38 are thus fastened to the cap and insulated therefrom. The opening in the cap is sufficiently large to prevent the rivet from making contact with the cap.

When the cap is threaded over the casing a short distance as shown in the drawing, the outer spring 32 makes electrical contact with the bottom of the zinc can and when contact spring 39 is pressed into contact with casing 21, current passes through the lamp, reflector, casing 21, contact 39, rivet 36, resistance wire 33, outer spring 32 to the battery zinc.

If it is desired to cut out the resistance the cap is screwed farther down upon the end of the casing until the short circuiting spring 34 makes electrical contact with the bottom of the zinc can which short circuits the resistance wire and on pushing contact spring 39, the circuit will be completed in the same manner as already described without including the resistance.

Instead of using a separate resistance, a material may be used in spring 32 which has both resistance and resiliency. In this event, the special resistance wire is eliminated and both functions would be performed by the spring member 32. It will also be evident that a flat spring could be used as a short circuiting arrangement instead of a coiled spring. The rivet itself if prolonged may be used to short circuit the resistance in which case spring 34 would be dispensed with. The use of the spring, however, is preferable. It will also be evident that it is not necessary to wind the resistance around the switch as in Figs. 1, 2 and 3 as it could also be placed in other locations in the casing, although the arrangement shown is preferable. The same is, of course, true of the modifications in Figs. 4 and 5.

The manner in which the arrangement described will be used will, of course, depend on the nature of the service. If a very bright light and narrow beam is desired, the resistance will be short circuited and the lens adjusted the correct distance from the incandescent filament. This arrangement is especially suitable for meter reading where the face of the instrument is sometimes out of reach and must be brightly illuminated to make it possible to distinguish the characters. In most cases, however, it will be found advantageous to use the resistance until the light becomes too dim and then to short circuit as described. When the light again becomes too dim, the lens will be adjusted to produce a narrower beam, thus further prolonging the service obtainable.

Having described my invention, what I claim is:

1. In an electric flashlight, a tubular member, a lamp reflector, a lens cap adjustable on said tubular member, a lens in said cap and a spring located between the reflector and the lens adapted to press the lens against the cap to allow adjustment of the position of the cap on the tubular member.
2. In an electric flashlight, a battery casting, a cap adjustable thereon, a contact closer secured to but insulated from said cap, a resistance in the cap and means to short circuit the resistance when said cap is adjusted on the casing a predetermined amount.
3. In an electric flashlight, a battery casting containing a seal and cap thereon, a contact closer secured to but insulated from said cap, a resistance inside the cap, a spring adapted to contact with a terminal of said battery, a contact member connected to said closer adapted to contact with said terminal when the cap is adjusted on the casing a predetermined amount, and a resistance connected between said spring and said contact member.
4. In an electric flashlight, a battery casting containing a cell, a cap adjustable thereon, an insulating disk inside the cap, a contact closer secured to said insulating disk, a coil spring inside the cap secured to the disk, a second coil spring secured to the contact closer, a coil of resistance wire secured to said disk, and connected to each of said springs.
5. In an electric flashlight, a battery cap having an insulating disk, a contact closer secured to the disk, a coil spring secured to the disk, a second coil spring of less axial length than the first spring secured to said contact closer, and a resistance wire wound on said disk having one end connected to one spring and the other end to the other spring.
6. In an electric flashlight, a battery having a terminal, a switch consisting of two spring members, insulating means therebetween, an electrical resistance conductor connected between said members and means for moving the members whereby the first one is made to touch the battery terminal and on further movement, the two members are made to contact with each other.
7. In an electric flashlight, a battery casting containing a battery with a terminal, a spring member secured at one end to said casing, a second spring member secured to the first member with insulating means therebetween, and a resistance wire wound around said members and having an end connected to each.

In testimony whereof, I hereunto affix my signature.

WILLIAM R. CLYMER.
